(57) **CLAIM**

We claim the ornamental design for a television with rollable display, as shown and described.

DESCRIPTION

FIG. 1 is a perspective view of a television with rollable display showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is an enlarged detail view of portion "8" encircled with broken line in FIG. 1;

FIG. 9 is a perspective view of the television with rollable display of FIG. 1, shown with the display partially unrolled in a first position of use;

FIG. 10 is a front elevation view thereof;

FIG. 11 is a rear elevation view thereof;

FIG. 12 is a left-side elevation view thereof;

FIG. 13 is a right-side elevation view thereof;

FIG. 14 is a top plan view thereof;

FIG. 15 is a bottom plan view thereof;

FIG. 16 is a perspective view of the television with rollable display of FIG. 1, shown with environment on the display partially unrolled in a first position of use;

FIG. 17 is a perspective view of the television with rollable display of FIG. 1, shown with the display partially unrolled in a second position of use;

FIG. 18 is a front elevation view thereof;

FIG. 19 is a rear elevation view thereof;

(Continued)

FIG. 20 is a left-side elevation view thereof;
 FIG. 21 is a right-side elevation view thereof;
 FIG. 22 is a top plan view thereof;
 FIG. 23 is a bottom plan view thereof;
 FIG. 24 is a perspective view of the television with rollable display of FIG. 1, shown with environment on the display partially unrolled in a second position of use;
 FIG. 25 is a perspective view of the television with rollable display of FIG. 1, shown with the display fully unrolled in a third position of use;
 FIG. 26 is a front elevation view thereof;
 FIG. 27 is a rear elevation view thereof;
 FIG. 28 is a left-side elevation view thereof;
 FIG. 29 is a right-side elevation view thereof;
 FIG. 30 is a top plan view thereof;
 FIG. 31 is a bottom plan view thereof; and,
 FIG. 32 is a perspective view of the television with rollable display of FIG. 1, shown with environment on the display fully unrolled in a third position of use.
 Broken lines illustrate portions of the television with rollable display that form no part of the claimed design. Additional broken lines shown on the display in FIGS. 16, 24 and 32, illustrate an example environment and form no part of the claimed design.
